US00D733713S

(12) **United States Design Patent**
Shim et al.

(10) **Patent No.:** **US D733,713 S**
(45) **Date of Patent:** **** Jul. 7, 2015**

(54) **SSD STORAGE DEVICE**(71) Applicant: **SAMSUNG ELECTRONICS CO., LTD.**, Suwon-Si, Gyeonggi-Do (KR)(72) Inventors: **Hyung-Sup Shim**, Seoul (KR); **Teuk-Mo Ahn**, Suwon-Si (KR)(73) Assignee: **Samsung Electronics Co., Ltd.**, Suwon-si, Gyeonggi-do (KR)(**) Term: **14 Years**(21) Appl. No.: **29/450,785**(22) Filed: **Mar. 22, 2013**(30) **Foreign Application Priority Data**

Jan. 4, 2013 (KR) 30-2013-0000586

(51) **LOC (10) Cl.** ..... **14-02**(52) **U.S. Cl.**USPC ..... **D14/435**(58) **Field of Classification Search**

(74) Attorney, Agent, or Firm — Volentine & Whitt, PLLC

(57) CLAIM

We claim the ornamental design for an SSD storage device, as shown and described.

DESCRIPTION

FIG. 1 is a perspective view of an SSD storage device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom view thereof.

1 Claim, 4 Drawing Sheets
